UNITED STATES PATENT OFFICE.

JOSEPH H. BRADLEY, OF PHILADELPHIA, PENNSYLVANIA.

DESIGN FOR AN ENVELOP-BLANK.

SPECIFICATION forming part of Design No. 31,391, dated August 15, 1899.

Application filed June 16, 1899. Serial No. 720,855. Term of patent 14 years.

To all whom it may concern:

Be it known that I, JOSEPH H. BRADLEY, a citizen of the United States, and a resident of the city of Philadelphia, State of Pennsylvania, have invented a certain new and original Design for an Envelop-Blank, of which the following is a full, clear, and exact description, reference being had to the accompanying drawing, forming part of this specification.

My invention relates to a design for envelop-blanks for use in mailing second or third class matter where it is required that one end of the envelop be open for inspection by the post-office authorities.

In the accompanying drawing the figure is a plan view of the blank spread out.

The leading feature of my design consists in the shape of the various flaps, the flap *a* being substantially rectangular in shape and of a size substantially corresponding to that of the body of the envelop, the edge *a'* being

slightly curved, as shown. The flap *b* is provided with slanting sides *b'* and is of a length about equal to one half the length of the body of the envelop. The flap *c* is very short ²⁵ and is provided with slanting sides *c'*. The flap *d* is of the form substantially as shown in the drawing and substantially similar to that used on the ordinary envelop. The coating of adhesive material is provided on the ³⁰ inner edge of this flap, as illustrated at *d'*.

Having thus described my invention, what I claim is—

The design for an envelop-blank substantially as herein shown and described. ³⁵

In witness whereof I have hereunto set my hand this 15th day of June, A. D. 1899.

JOSEPH H. BRADLEY.
